UNITED STATES PATENT OFFICE.

FRANCIS C. BATES, OF NEWPORT, VERMONT.

DESIGN FOR A HOOP.

SPECIFICATION forming part of Design No. 24,405, dated June 18, 1895.

Application filed April 20, 1895. Serial No. 546,561. Term of patent 7 years.

To all whom it may concern:

Be it known that I, FRANCIS C. BATES, a citizen of the United States, residing at Newport, in the county of Orleans and State of Vermont, have invented and produced a new and original Design for a Rolling-Hoop, of which the following is a specification, reference being had to the accompanying drawing, in which a rolling-hoop embodying my design is represented in plan or side view.

The leading feature of the design is the central star-like figure, or portion, A, which con-

sists of a circular plate or disk, 1, having a double series of radial projections, 2 and 3. Between this central figure, A, and the hoop, 15 B, is arranged a series of cords, C.

What I claim is—

The design for a rolling-hoop, substantially as shown and described.

FRANCIS C. BATES.
